BREECH OPERATING MECHANISM FOR
AUTOMATIC FIREARMS

Clarence E. Simpson, Springfield, Mass., assignor
to the United States of America as represented
by the Secretary of War

Original application June 7, 1946, Serial No.
675,124. Divided and this application February
4, 1948, Serial No. 6,153

7 Claims. (Cl. 89—167)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a breech timing mechanism for automatic firearms and more particularly to a device for insuring that the breech block will go into battery position in properly timed relationship with the other breech elements of the firearm.

This application is a division of my copending application for Firearm, Serial No. 675,124, filed June 7, 1946, now matured in Patent No. 2,555,379 dated June 5, 1951.

In the firearm referred to in the above-mentioned copending application, there is provided a recoiling barrel, barrel extension, breech block, and breech block carrier which are arranged for longitudinal reciprocation within the receiver. The breech block is constructed to slide along an inclined plane on the breech block carrier. When the recoiling members are in the extreme recoiled position, the recoil spring acts to return the barrel and barrel extension forwardly and the breech block and breech block carrier tend to move along with the barrel and barrel extension. However, the breech block carrier is retained in the recoiled position by a latch. Thus only the breech block can move forwardly with the barrel and barrel extension. However, the breech block is permitted to travel downwardly on the breech block carrier a sufficient amount to permit unlocking of such block from the barrel extension and when such occurs the breech block is held on the breech block carrier and the barrel and barrel extension proceed to the battery position.

After the barrel and barrel extension have reached battery position, the breech block is released from the breech block carrier and then both the block and carrier go forwardly into breeched position. It is most essential that the breech block be not released until the barrel and barrel extension are in battery position as the breech block and carrier could be released at an inopportune moment and come forwardly at the wrong time thus introducing the possibility of jam and premature discharge of a live round in the feedway of the firearm.

Accordingly it is an object of this invention to provide a device to insure that the breech block will go into battery position in properly timed relationship with the other reciprocating breech members of the firearm.

The specific nature of the invention as well as

other objects and advantages thereof will clearly appear from a description of a preferred embodiment as shown in the accompanying drawings in which:

Fig. 1 is a fragmentary side view of a firearm showing the recoiling parts in the battery position.

Fig. 2 is a view similar to Fig. 1 but showing the recoiling elements in the extreme recoiled position and showing the depressor bar in its rearmost position and contacting the roller of the depressor.

Fig. 3 is a view similar to Figs. 1 and 2 showing the barrel and barrel extension approaching battery position.

Fig. 4 is a view similar to Fig. 3 showing the barrel and barrel extension in battery position but with the breech block in the fully depressed state and also showing the depressor bar urged to its extreme forward position by the barrel extension.

Fig. 5 is an enlarged detail side elevational view showing the breech block fully depressed by the depressor.

Fig. 6 is an enlarged detail opposite side elevational view showing the stop secured to the inclined arm of the breech block.

In the accompanying drawings there is shown a firearm embodying this invention. Such firearm comprises mainly a receiver 10, a barrel 11, barrel extension 12, breech block 13, and a breech block carrier 14. Barrel extension 12 is preferably threadedly secured to barrel 11 and the barrel extension 12 is slidably mounted in receiver 10 for longitudinal reciprocating movement. A feedway member 15 is pivotally mounted on receiver 10 and substantially surrounds barrel 11. Barrel extension 12 is shown in Fig. 1. Breech block 13 and carrier 14 are slidably mounted in receiver 10 and are arranged for longitudinal reciprocating movement as will be presently described.

Breech block 13 comprises a substantially V-shaped member having a vertical arm 16 and a rearwardly sloped arm 17. A T-slot (not shown) is provided on the forward vertical face of arm 16 to receive the head of a cartridge 45. A plurality of integral locking lugs 18 are provided on the sides of vertical arm 16 of breech block 13 which engage corresponding lugs in barrel extension 12 when breech block 13 is raised into battery position with barrel extension 12. A breech block stop 19 is secured to the inclined arm 17 of breech block 13 near the top thereof as by a screw 20. The stop 19 comprises a substantially

rectangular member provided on the right side thereof with a downwardly projecting lug 47 as shown in Fig. 6. A rear surface 48 of downwardly projecting lug 47 engages an integral lug 49 on breech block carrier 14 to control the upward movement of breech block 13 on carrier 14. An upwardly projecting lug 50 is provided on the other side of stop 19 and the lower corner of such lug is engaged by a breech block depressor 21 being provided with locking means to be later described.

Breech block carrier 14 comprises a horizontal arm 22 and an integral upwardly inclined arm 23 as shown in Figs. 1 and 4. Breech block 13 is secured to the upwardly inclined arm 23 of breech block carrier 14 in such a manner that the breech block 13 will slide along such face relative to the carrier.

Breech block depressor 21 is pivotally mounted on breech block carrier 14 as shown in Figs. 1, 2, 3, and 4. Breech block 13 is arranged to be disengaged from breech block carrier 14 by depressor 21 at the desired time as will be later described. Depressor 21 comprises a body portion 24 having in the center thereof an integral upright arm 25. The extreme upper portion 46 of arm 25 is bent forwardly somewhat as shown in the above-mentioned figures and a notch 26 is provided in the uppermost corner thereof to engage stop 19 thereby locking breech block 13 in the battery position.

Depressor 21 is pivotally mounted by a transverse pin 27. Depressor 21 is fixedly secured to pin 27. Such pin is journaled within a suitable transverse hole in the breech block carrier 14. The bottom surface of the body portion 24 of depressor 21 rests on the top surface of arm 22 of carrier 14. The forward edge of body portion 24 is rounded as at 28 to permit rotation of depressor 21 about the axis of pin 27. A plunger 29 suitably spring biased is vertically mounted within a downwardly opening hole in the rear edge of body portion 24 to bias arm 25 in a counterclockwise direction to insure that notch 26 will engage the lower corner of stop 19. A roller 30 is mounted on a fixed stud 31 on the side of body portion 24 as shown in the drawings.

A depressor bar 32 comprises a substantially rectangular bar slidably mounted on the left side of the firearm for reciprocating longitudinal movement. A latch 33 is pivotally mounted between two integral lugs 34 provided near the forward end of depressor bar 32 by a suitable pin which is supported by such lugs. Latch 33 is biased inwardly against barrel extension 12 by a suitable spring (not shown). Latch 33 engages a stud 35 provided on the lower right hand corner of barrel extension 12 to carry depressor bar 32 forwardly as will be presently described.

An upwardly sloped cam surface 36 is formed on a vertical lug 37 provided on the rear end of depressor bar 32. Lug 37 also projects inwardly to engage roller 30 on depressor 21. An overhanging shelf 38 is provided on an integral raised lug 39 somewhat ahead of lug 37. Shelf 38 projects over the forward edge of cam surface 36 and is provided to engage roller 30 so that depressor 21 may be disengaged from stop 19, thus permitting breech block 13 to become separated from barrel extension 12. Two longitudinally disposed slots 40 and 41 are provided at the rear and forward ends of bar 32, respectively, through each of which is inserted a screw 42 which engages suitable threaded holes in receiver 10. A washer 43 is preferably placed under the

head of each screw 42 and screws 42 are so adjusted as to permit free longitudinal movement of depressor bar 32 within the limits of slots 40 and 41.

Depressor bar 32 functions in the following manner: Upon depressing depressor 21, the breech action, comprising essentially breech block 13 and breech block carrier 14, may be manually retracted rearwardly. A cartridge strip 44 containing cartridges 45 may then be inserted in feedway 15 whereupon the action is permitted to close. Breech block 13 then rises vertically to the closed locked position as shown in Fig. 1 thereby engaging the rim of the first cartridge contained in strip 44 in the T-slot provided in the face of breech block 13. To feed the cartridge now held in the face of breech block 13, depressor 21 is disengaged from stop 19 as previously described so that breech block 13 can drop downwardly sufficiently to disengage lugs 18 from the corresponding lugs in barrel extension 12 thereby unlocking such breech block from barrel extension 12. The action is then withdrawn rearwardly until the rear end of carrier 14 is approximately $\frac{1}{8}$ " from the end of its extreme recoil position. However, when the action is approximately 2" from the end of such stroke, roller 30 on depressor 21 engages cam surface 36 on depressor bar 32. Depressor portion 46 contacting stop 19 then starts breech block 13 downwardly on carrier 14. When roller 30 strikes the vertical portion of cam 36, as shown in Fig. 4, depressor 21 has fully depressed breech block 13 so that the cartridge held in such breech block is aligned within the chamber of barrel 11. While the gun is being manually charged, depressor bar 32 is held stationary in the forward position through the connection of such bar to barrel extension 12 by stud 35. Breech block 13 then moves forwardly to chamber the cartridge held in the face thereof, and upon chambering the round the horizontal movement of the breech block is changed to a vertical movement thereby engaging lugs 18 with corresponding lugs in breech block 13 to lock such breech block securely to barrel extension 12.

When the round is fired, the action, along with the barrel and barrel extension recoil rearwardly and near the end of the recoil stroke roller 30 on depressor 21 passes under shelf 38 on depressor bar 32. This causes depressor 21 to rotate clockwise and become disengaged from stop 19 on breech block 13. Stud 35 on barrel extension 12 strikes the forward face of lug 39 to carry depressor bar 32 to the rear as shown in Fig. 2. Such bar is forced rearwardly to prevent roller 30 from binding on cam surface 36. Barrel 11 and barrel extension 12 are started forwardly on the counterrecoil stroke by the recoil spring (not shown). The carrier is retained in the rearmost position as shown in Fig. 4 by a carrier latch (not shown). Forward movement of barrel 11 and barrel extension 12 forces block 13 to slide downwardly on the inclined arm 23 of carrier 14 until the locking lugs 18 on block 13 are aligned with corresponding openings in barrel extension 12 (not shown).

Thus barrel 11 and barrel extension 12 become unlocked from breech block 13 and are moved into battery position by the bias of the barrel spring (not shown). Breech block 13 is then yieldingly retained in the unlocked position on carrier 14 until stud 35 on barrel extension 12 strikes latch 33 on depressor bar 32. Such bar is then carried forward by barrel 11 until such

barrel comes to a final stop at its forward position as shown in Fig. 4. As the depressor bar 32 moves forwardly, shelf 38 moves off the roller 30 and the cam surface 36 on depressor bar 32 guides roller 30 and partially rotates depressor 21 in a counterclockwise direction as viewed in Fig. 4. This forces breech block 13 down the inclined surface of carrier 14 thereby aligning the live round contained in the breech block with the axis of the bore. Downward travel of the breech block on carrier 14 strikes the carrier latch (not shown) thereby releasing such latch and permitting the breech block to go forwardly to the battery position.

It is therefore apparent to those skilled in the art that there is here provided a mechanism that will positively insure that the breech block of an automatic firearm will go into battery position in timed relationship with the cooperating elements of the breech mechanism.

I claim:

1. In a firearm having a receiver, a barrel extension slidably mounted in said receiver for reciprocating movement, a barrel secured to said barrel extension, a breech block carrier slidably mounted in said receiver for reciprocating movement parallel to said barrel and barrel extension movement, a breech block guide surface on said carrier angularly disposed relative to the path of movement of said carrier and located rearwardly of said barrel extension, a breech block slidably mounted relative to said guide surface for reciprocal movement between two spaced positions on said guide surface, a stop secured to said breech block, a depressor pivotally secured to said carrier constructed and arranged to engage said stop, said depressor being provided to hold said breech block on said carrier in the uppermost of said two spaced positions, and means for disengaging said depressor from said stop.

2. The combination defined in claim 1 wherein said means comprises a bar slidably mounted for limited longitudinal movement on said receiver, a catch on one end of said bar arranged to be engaged by a stud on said barrel extension, and a cam on the other end of said bar being provided to rotate said depressor when said barrel stud engages said catch as said barrel and barrel extension move into battery position whereby said depressor forces said breech block downwardly on said carrier to the lowermost of said two spaced positions.

3. The combination defined in claim 1 wherein said means comprises a stud secured to said barrel extension, a bar slidably mounted for longitudinal movement on said receiver, and an upwardly projecting shelf being provided adjacent the rear end of said bar constructed and arranged to rotate said depressor thereby disengaging said depressor from said stop when said stud engages the forward part of said shelf as said barrel extension moves into the recoil position.

4. In a firearm having a receiver, a barrel extension slidably mounted in said receiver for reciprocating movement, a breech block carrier slidably mounted in said receiver for reciprocating movement parallel to said barrel extension movement, a breech block guide surface on said carrier angularly disposed relative to the path of movement of said carrier and located rearwardly of said barrel extension, a breech block slidably mounted relative to said guide surface for reciprocal movement between two spaced positions on said guide surface, a stop secured to said

breech block, a depressor pivotally secured to said carrier constructed and arranged to engage said stop, said depressor being provided to hold said breech block on said carrier in the uppermost of said two spaced positions, and means for rotating said depressor to depress said breech block to the lowermost of said two spaced positions.

5. In a firearm having a receiver, a barrel extension slidably mounted in said receiver for reciprocating movement, a breech block carrier slidably mounted in said receiver for reciprocating movement parallel to said barrel extension movement, a breech block guide surface on said carrier angularly disposed relative to the path of movement of said carrier and located rearwardly of said barrel extension, a breech block slidably mounted relative to said guide surface for reciprocal movement between two spaced positions on said guide surface, a projecting stop secured to said breech block, and locking means for engaging the under surface of said stop to hold said breech block on said carrier in the uppermost of said two spaced positions.

6. In a firearm having a receiver, a barrel extension slidably mounted in said receiver for reciprocating movement, a breech block carrier slidably mounted in said receiver for reciprocating movement parallel to said barrel extension movement, a breech block guide surface on said carrier angularly disposed relative to the path of movement of said carrier and located rearwardly of said barrel extension, a breech block slidably mounted relative to said guide surface for reciprocal movement between two spaced positions on said guide surface, a protruding stop secured to said breech block, and a spring-biased depressor pivotally secured to said carrier and provided with a substantially upright arm with a notch therein arranged and constructed to engage the lower surface of said stop in the uppermost of said two positions.

7. In a firearm having a receiver, a barrel extension slidably mounted in said receiver for reciprocating movement, a breech block carrier slidably mounted in said receiver for reciprocating movement parallel to said barrel extension movement, a breech block guide surface on said carrier angularly disposed relative to the path of movement of said carrier and located rearwardly of said barrel extension, a breech block slidably mounted relative to said guide surface for reciprocal movement between two spaced positions on said guide surface, a protruding stop secured to said breech block, a projecting lug on said breech block carrier arranged to limit the upward movement of said breech block when the upper surface of said stop is in contact with said lug, and locking means for engaging the lower surface of said stop to hold said breech block on said carrier in the uppermost of said two spaced positions.

CLARENCE E. SIMPSON.
